UNITED STATES PATENT OFFICE

2,561,940

ENGINE STARTER MESHING MEANS

Charles S. Metsger, Atlantic Highlands, N. J., assignor to Bendix Aviation Corporation, Teterboro, N. J., a corporation of Delaware

Original application November 13, 1947, Serial No. 785,723. Divided and this application June 13, 1950, Serial No. 167,778.

4 Claims. (Cl. 123—179)

1

This application is a division of application Serial No. 785,723, filed November 13, 1947, now Patent No. 2,548,268, and relates to engine starters, and particularly to a starter of the self-contained high-speed type, in which the turning motion is transmitted through a rotatable output member or jaw having its axis of rotation in line with the axis of rotation of an engine member.

Among the objects of the invention are to provide a starter structure or system of greatly increased power and reduced weight as for aircraft service and which shall avoid the disadvantages of overrunning clutches, such as destruction of parts by centrifugal force upon failure of operation, completely separate the high speed meshing starter and engine members, reduce critical tolerances, mesh the starter and engine members prior to a given rate of operation of the starter, and have other advantages.

Another object is to provide a device of the above-indicated character which shall be simple and durable in construction, economical to manufacture, and effective in its operation.

The above and other objects and features of the invention will appear more fully hereinafter from a consideration of the accompanying drawings wherein one embodiment of the invention is illustrated by way of example.

In the drawing, the single figure is a diagram of a system including a view in section of a starter of the invention.

The device comprises a rotatable engine-engaging member 10 adapted for axial extension from and a position meshed with an engine member (not shown) for starting the engine. The device further comprises an axially stationary rotative nut 14, means including driving means 18 adapted to rotate the nut 14, a screw shaft element 20 axially movable relative to, and rotatively movable by, the nut 14 associated with the engine-engaging member 10 for rotating the latter. The screw shaft element 20 is adapted to move the engine-engaging member 10 in its axial extension movement engaging it to the engine member.

Means including spring means 26 cooperate with the meshing rod 22 to oppose movement of the member 10 by the screw shaft 20. Means 28 are also adapted to effect the movement of the screw shaft element 20 through the intermediary of a yieldable medium, which in this case is compressed air. Means 34 provide for first initiating movement of the screw shaft element 20 and following with rotative action of the engine-engaging member 10 by the driving means 18.

The driving means 18 comprises a plate 150 adapted for attachment to the rotor of a turbine

2

or other motor (not shown), and provided with a female spline extension 152 adapted to receive a cooperating male spline shaft 154, journaled by a bearing 156 in an end plate 158 of a housing 38. The plate 150 is held axially relative to the shaft 154 between the bearing 156 and a nut structure 160 in a cavity of the extension 152.

A portion 162 of the housing 38 has a chamber 164 in which is disposed a flange 166 of the shaft 154 which is secured, as by a ring 168 and screws 170, to a closed end wall 172 of a barrel 174 journaled in the housing portion 162 as by bearings 176.

The spline nut 14, in the barrel 174, is connected to the latter by a torque-limiting friction disc pack 178 having interlayered discs fixed to the nut 14 and the barrel 174, respectively, and axially biased together, as by helical springs 180 and a ring nut 182 threaded in the opposite end of the barrel 174.

The screw shaft 20, having long-lead thread relation to the nut 14 therein, has an axially slidable spline connection 184 to the starter clutch jaw member 10.

The jaw 10 and the screw shaft 20 are connected by the meshing rod 22 having a head 186 and extending through an aperture in the jaw 10, which aperture is closed by a seal 188 biased against the jaw by a spring 190 extending into the screw shaft 20. A nut 191 is mounted on the rod 22 at the left of the jaw 10.

The screw shaft 20 is limited in its axial movement to the right, as viewed in the drawing, by engagement with a disc 192 against the barrel end wall 172 and, in its axial movement to the left by a usual shoulder on the screw shaft 20 with a shoulder on the spline nut 14. A ring seal structure 194, not germane to the present invention, cooperates between a baffle portion 196 of the housing 38 and the jaw member 10.

The screw shaft 20, instead of being for advancement by rotation of the nut 14 as in a usual direct-cranking starter having friction means adjacent to the seal 194, the latter of which is not true in this case, is adapted as by seal rings 198 and 200 in grooves of the screw shaft around the rod 22 and the shaft 20, respectively, for action as a piston responsive to fluid pressure introduced into the chamber 164.

An inlet 202 admits fluid to the chamber 164 for passage, indicated by arrows, through passageways 204, 206 and 208, see lower central portion of the figure, to the screw-shaft piston 20.

The means 28 comprises an electrical unit 210 having a plunger 134 which has its lower end constructed as the movable element of a valve 212 for controlling the flow of fluid, such as com-

3
pressed air, form a source 214 through a pipe 216, the valve 212 and a pipe 218 to the inlet 202.

The unit 210 includes a solenoid coil 130 surrounding a hollow armature core 132 carrying the plunger 134 axially movable relative thereto. The plunger 134 has a head 136 normally held against a seat 138 of the core 132 by a spring 32, which in turn is backed and held in place by a locking ring 140 positioned in a groove of the core 132. Downward movement of the core 132, as shown, is limited by stop means 142. Spring contacts 143, movably carried by the plunger 134, constitutes a bridging contact member for stationary contact elements 144 to energize the motor 220.

Means 34 provide for first initiating the axial extension movement of the screw shaft element 20, during which, prior to rotation of the shaft 154, the element 20 will rotate, but not under the power of the shaft 154.

A device 220 corresponds either to a motor or another electrical unit for starting a turbine and is controlled as by a switch 92 relative to a source of electromotive force 90.

In operation, with the parts in the inactive positions shown, when the switch 92 is closed, current flows from one side of the source 90 through a conductor 222, the switch 92, the solenoid coil 130 of the unit 210, and a conductor 224 to the opposite side of the source 90. This action first opens the valve 212 to cause flow of fluid from the source 214 through the pipe 216, the valve 212 and the pipe 218 to the inlet 202, and into the chamber 164. From the latter, the fluid flows, as indicated by arrows, through the passageways 204, 206 and 208 to the rear of the piston screw shaft 20 to advance the latter to the left and to push the member 10 through the intermediary of the spring means 180 into engagement with the engine member, during which the shaft 20 will rotate in the stationary unit 14 to rotate the member 10. The timing of the opening of the valve 212 and the closing of the circuit of the device 200 is, in this instance, such that the shaft piston 20 will cause the rotating member 10 to engage the engine member before driving operation of the shaft 154. Thus, the member 10 has a chance to mesh before the application of rotative power. If, however, butting should occur, meshing will be insured upon the first application of rotative driving power prior to the attainment of a certain rate of speed by the member 10.

The timing aforesaid may be varied such that power rotation may be applied upon or at any time before or after engagement of the member 10 with the engine member as desired or dependent upon conditions of, or circumstances surrounding, a particular case.

The device has an advantage over other forms of meshing in that it utilizes standard parts of former starters not previously operable in the same manner. The invention therefore provides for a very great range of its application and uses, and is an improvement generally in its field.

Although only one embodiment of the invention has been illustrated and described various changes in the form and relative arrangement of the parts may be made to suit requirements.

What is claimed is:

1. In an engine starting mechanism, the combination of a rotatable engine-engaging member adaptable for axial extension and retraction movements, respectively, between a position re-

leased from and a position meshed with an engine member for starting the engine, an axially stationary rotative nut, means including an electric motor adapted to rotate the nut, a screw shaft element axially movable relative to, and rotatively movable by the nut and associated with the engine-engaging member for rotating the latter, a meshing rod element responsive to pressure to move said engine-engaging member in its said axial extension movement, means including spring means cooperating with said rod element for opposing said extension movement of the engine-engaging member, means for effecting said pressure, means responsive to the operation of said pressure effecting means for controlling the circuit of said motor; and means adapted to actuate said pressure effecting means to operate said rod element to effect said extension movement and said circuit controlling means to energize the motor.

2. In an engine starting mechanism, the combination of a rotatable engine-engaging member adapted for axial extension and retraction movements, respectively, between a position released from and a position meshed with an engine element for starting the engine, an axially stationary rotative nut, driving means adapted to rotate the nut, a screw shaft element axially movable relative to and rotatively movable by the nut and associated with the engine-engaging member for rotating the latter, a meshing rod element, said meshing rod element being adapted to move said engine-engaging member in its said axial extension movement engaging it to said engine element, spring means cooperating with said meshing rod element to oppose said movement of the engine-engaging member by said meshing rod element; a first power means including a source of fluid pressure to actuate said meshing rod element, and a second independent power means to effect rotation of said nut through said driving means, and control means operated by said first power means for initiating operation of said second power means and rotative action of said engine-engaging member by said driving means following initiation of the axial extension movement of the engine-engaging member by said first power means so that complete meshing of the engine-engaging member with the engine element is accomplished.

3. The combination defined by claim 2 in which said control means includes a solenoid, a valve to control said source of fluid pressure, and a switch operated by the solenoid to initiate operation of said second power means.

4. The combination defined by claim 2 in which said control means includes a solenoid operated valve to control said source of fluid pressure, and means responsive to operation of said valve to initiate operation of said second power means.
